UNITED STATES PATENT OFFICE.

NEWTON J. WIGGINTON, OF WINCHESTER, VIRGINIA.

SPRAYING-COMPOUND MIXER.

1,036,392.

Specification of Letters Patent. Patented Aug. 20, 1912.

Application filed April 6, 1912. Serial No. 688,941.

To all whom it may concern:

Be it known that I, NEWTON J. WIGGINTON, a citizen of the United States, and a resident of Winchester, in the county of 5 Frederick and State of Virginia, have made certain new and useful Improvements in Spraying-Compound Mixers, of which the following is a specification.

My invention relates to improvements in 10 devices for mixing spraying compounds, and it consists in the combinations, constructions and arrangements herein described and claimed.

An object of my invention is to provide a 15 device in which substances such as sulfur and lime may be mixed with water so as to insure the production of a homogeneous substance.

A further object of my invention is to 20 provide a device which will automatically mix the ingredients of the spraying solution, said device being provided with arms or scrapers which tend to scrape the solid portions of the mixture toward the central 25 part of the device, thereby preventing the clogging of the device.

A further object of my invention is to 30 provide means by which the larger solid portions of the mixture may be broken up.

A further object of my invention is to 35 provide a device having a series of scrapers, certain of said scrapers having a raking movement with means for adjusting the movements and positions of the scrapers.

Other objects and advantages will appear in the following specification, and the novel features of the device will be particularly pointed out in the appended claims.

My invention is illustrated in the accompanying drawings forming part of this application in which—

Figure 1 is a vertical sectional view through the device, Fig. 2 is an enlarged plan view of one of the tanks, and Fig. 3 45 is a sectional view along the line 3—3 of Fig. 2.

In carrying out my invention I provide a longitudinal tank 1, preferably made of metal which is disposed above the combustion chamber 2 of a furnace. The exit flue 3 of the furnace is connected by means of a pipe 4 to a chamber 5 underneath the second tank 6, the chamber 5 being in turn connected to the escape flue 7. The tank 6 is 55 situated, as shown, above the level of the

tank 1, and is connected with the latter by means of an inclined pipe 8, which is provided with a valve 9.

The details of the main mixing tank 1 are best shown in Figs. 2 and 3. It will be seen 60 that the tank is provided at each end with a bearing 10. A description of one of these bearings will suffice, since they are both alike. They consist of blocks 10^a provided with a semi-cylindrical bearing portion 10^b 65 arranged to receive a rod 11. The rod is kept in position by means of a plate 10^c, which slides above the rod, but beneath four lugs such as that shown at 10^d. The plate is limited in its movement by a stop member 70 10^e at one end of the block 10^a. A bolt 10^f secures the plate 10^c in position. The rod 11 extends through both ends of the device. At one end it is connected by a pivoted rod 12 with a turn buckle 13, the latter being 75 connected by the rod 14 with a slotted arm 15 on the end of the crank arm 16.

Referring now more particularly to Fig. 2, it will be seen that I have provided a frame consisting of the longitudinal members 17 and the cross strips 18 underneath the members 17. The latter are formed of angle irons and are tapered at their ends as shown at 18^x in Fig. 3. These cross strips serve a double purpose in that they 80 form part of the frame and act as scrapers 85 in a manner hereinafter described. Secured to the longitudinal members 17 at each end thereof are the uprights 19, these uprights are adjustable longitudinally of the strips 17, and for this purpose the base member 19^y of the uprights 19 is slotted, as shown at 19^z, and bolts 19^w pass through the slots 90 into the members 17.

At each end of the device is a pivoted frame consisting of the arms 20, which are pivoted to the uprights 19 and are bent downwardly at their ends, as shown in Fig. 1. To these arms are secured side members 21 and 22. The side members on opposite 95 sides of the tank are connected together by means of a rod 23, as shown in Fig. 3. A scraper 24 is carried by the arms 20.

Near the ends of the tank on each side thereof is a block or plate 25, which is secured to the inner portion of the tank and to which is pivotally secured an arm 26 designed to rest normally in an inclined position upon a step 27 (see Fig. 2). Between the pivot of the arm 26 and the end of the 100

tank, the block or plate 25 is curved outwardly, as shown at 25*. There are four of these blocks or plates, as shown in Fig. 2.

Secured to the central cross members or 6 scrapers 18 is a hollow casting 28, which is corrugated at 28* on its exterior side portions. The casting is slotted at 28* (see Fig. 1) to permit the entrance of bolts 29, these bolts having plates 30 corrugated to mesh 10 with the corrugations of the casting 28. The rod 11 has a downwardly extending arm 31, which is suitably braced at 32, this arm extending between the two bolts 29, as shown.

From the foregoing description of the various parts of the device, the operation 15 thereof may be readily understood. The water for the mixture is heated in the tank 6 from whence it may be drawn into the tank 1 through the pipe 8. The lime and 20 sulfur together with the hot water are placed in the tank 1, the cover 34 which is suspended by the cable 35 is let down, and the apparatus is started. The revolution of the 25 crank 16, which is secured to the engine shaft (not shown) causes the reciprocation, of the rod 11 and of the arm 31. In Fig. 1, the rod is illustrated as moving toward the right of the figure. As the ends of the rod 23 engage the inclined arms 26, the frame bearing the scraper 24 is raised. The farther the rod is pushed toward the right, the higher the scraper is raised, since the ends of the rod 23 have to ride up the inclined plane. When the rod 23 reaches the end 35 of the arm 26, it suddenly drops off, thereby permitting the scraper 24 to descend to the bottom. The rod 23 at the opposite end of the device will ride under its arm, lifting the latter from its stop pin 27, so that the 40 scraper will remain on the bottom as long as the stroke is toward the center of the tank. When the stroke is reversed, however, it will ride up the inclined arm while the rod 23 at the right of the figure will ride underneath its arm 26. This imparts a raking 45 motion to the scrapers 24 and tends to constantly pull the lime and sulfur away from the ends and toward the center. The other scrapers merely move backward and 50 forward along the bottom of the tank.

The stroke of the scraping device may be varied in a number of ways. By manipulating the turn buckle 13, it is obvious that the effective length of the pitman which 55 connects the arm 15 with the rod 11 may be lengthened or shortened, thus varying the stroke. The position of the scraping frame with respect to the arm 31 may be varied by shifting the bolts 19 along the slotted casting 28. Moreover by adjusting the distance between the bolts, the rod 11 may be moved without necessarily moving the scrapers. The pivoted raking members at each end of the scraper device may be adjusted by shifting 60 the uprights 19, which, as stated before,

is accomplished by loosening the bolts 19, and shifting the supports of the uprights 19. These adjustments permit of the regulation of the stroke so as to get an entirely homogeneous mixture. The mixture may be 70 drawn off at the spout 33.

The apparatus described above is capable of producing a maximum amount of the spraying mixture with a minimum amount of heat, since the cover 34 may be lowered to keep the heat within the tank. If, however, the heat should rise too fast or too suddenly the cover may be raised slightly to 75 permit the heat to escape.

I claim:

1. In a mixing device, a tank, a reciprocating scraping device disposed within said tank, said device comprising a pair of longitudinal members, a series of transverse scrapers secured to said longitudinal members, a frame pivotally secured to said scraping device at each end thereof, each of said frames being provided with a scraper, and means carried by the side walls of said tank for engaging each frame on its outward movement to cause the raising of the latter. 80

2. In a mixing device, a tank, a reciprocating scraping device disposed within said tank, said device comprising a pair of longitudinal members, a series of transverse scrapers secured to said longitudinal members, a frame pivotally secured to said scraping device at each end thereof, each of said frames being provided with a scraper, and means carried by the side walls of said tank for engaging each frame on its outward movement to cause the raising of the latter, the frame being freed from the raising means at the end of its outward movement to bring the scraper into engagement with 90 material in the tank. 100

3. In a mixing device, a tank, a reciprocating scraping device disposed within said tank, said device comprising a pair of longitudinal members, a series of transverse scrapers secured to said longitudinal members, a frame pivotally secured to said scraping device at each end thereof, each of said frames being provided with a scraper, a pair of pivoted inclined arms carried by the side walls of said tank at each end thereof, and a stop pin for each arm, said arms being arranged to engage the frame on its outward movement, thereby causing the raising of the frame and scraper, the return movement of the frame serving to lift the arms from their stop pins. 110

4. In a mixing device, a tank, bearings at each end thereof, a rod carried by said bearings, means for reciprocating the rod, a 125 downwardly projecting arm carried by said rod, a scraping device disposed within said tank and arranged to be engaged by said arm, means for adjusting the position of the arm relative to said scraping device, said 130

scraping device comprising a pair of longitudinal members, a series of transverse scrapers secured to said longitudinal members, a frame pivotally secured to said scraping device at each end thereof, each of said frames being provided with a scraper, a pair of pivoted inclined arms carried by the side walls of said tank at each end thereof, and a stop pin for each arm, said arms being arranged to engage the frame on its outward movement, thereby causing the raising of the frame and scraper, the return movement of the frame serving to lift the arms from their stop pins.

5 15 5. In a mixing device, a tank, bearings at each end thereof, a rod carried by said bear-

ings, means for reciprocating the rod, a downwardly projecting arm carried by said rod, a scraping device disposed on the bottom of said tank, a slotted casting carried 20 by said scraping device and provided with corrugated sides, bolts arranged to pass through said casting, said downwardly extending arm being arranged to extend between said bolts, the engagement of the 25 downwardly extending arm with the bolts serving to reciprocate the scraper.
